UNITED STATES PATENT OFFICE.

HARRY E. GREEN, OF HAMPTON, NEW BRUNSWICK, CANADA.

FIGURE WHEELED TOY.

1,374,296.

Specification of Letters Patent. Patented Apr. 12, 1921.

Application filed July 17, 1919. Serial No. 311,589.

To all whom it may concern:

Be it known that I, HARRY E. GREEN, a subject of the King of Great Britain, residing at Hampton P. O., Kings Co., New 5 Brunswick, Canada, have invented certain new and useful Improvements in Figure Wheeled Toys, of which the following is a specification.

This invention relates to toys, and more 10 particularly to a toy, simulating a human person, the legs of which are operated, to simulate walking or riding action during movement of the toy, the said movement of the legs being imparted thereto through the 15 medium of a crank shaft and wheel, which may be either rolled over a suspending cord or string, or rolled over the ground in the manner of trundling toys.

A further object of this invention is to 20 provide a toy as specified, in which a supporting frame for the crank axle upon which the operating wheel is mounted extends upwardly into the trestle of the figure, forming a firm and secure support for the 25 axle and wheel and also providing a structure wherein the movable parts will, for a portion of their length extend in close proximity to or against the side portions of the torso, thereby steadyng their movement.

30 A further object of the invention is to provide a slot in the upper or head portion of the movable legs which opens at the uppermost portions of the legs and engages over a suitable pin carried by the body or 35 torso, for guiding the movement of the legs.

Other objects of the invention will appear in the following detailed description taken in connection with the accompanying drawings, forming a part of this specification, and in which drawings,

40 Figure 1 is a fragmentary front elevation of said improved toy.

Fig. 2 is a side elevation of the toy.

45 Fig. 3 is a cross section taken on the line 3—3 of Fig. 1.

Fig. 4 is a front elevation of a modified form of the toy.

Fig. 5 is a side elevation of the modified form of toy and

50 Fig. 6 is a section taken on the line 6—6 of Fig. 4.

Referring more particularly to the drawings, wherein like characters indicate like and corresponding parts, throughout the 55 several views, the torso or body 10 of the toy may be made to simulate a human form,

and the lower end of this torso is provided with a cut out portion 11 forming depending arms 12. A rectangular supporting frame 13 extends upwardly into the recess 60 11, fitting snugly against the inner sides of the arms 12 and against the upper edge of the recess being attached to the arms by nails or analogous attaching means 14.

The frame 13 rotatably supports an axle 65 15, which axle has crank portions 16 and 17 formed upon its opposite ends. A wheel 18 is mounted upon the axle 15 and it preferably has a concaved or smooth periphery, for engagement over the string or cord 19 70 75 which may be positioned at an incline so that the toy will travel downwardly thereover, and in so traveling, rotary movement will be imparted to the wheel 18 and from the wheel to the axle 15. The legs 20 and 21 80 of the body are connected to the crank portions 16 and 17 respectively of the axle 15 and they are provided with longitudinally extending slots 22 in their upper portions which slots open out through the upper edge 85 of the legs as clearly shown in Fig. 2 of the drawings. The slots 22 extend at an incline with respect to the vertical and they receive therethrough portions of a pin 23. This pin 23 has an enlarged head 24 upon its outer 90 end to prevent the slotted ends of the legs 20 from moving laterally off the ends of the pin. However, the slot 22 will permit limited up and down movement of the legs 20 and 21 over the pin 23, so that during 95 the rotation of the axle 15, the legs 20 and 21 will be moved to simulate movement of the person thereby lending attractiveness to the toy.

A rod 25 is attached centrally to the bottom of the frame 13, and it has a counter-balancing weight 26 attached to its lower end for balancing the toy upon the cord or string 19. While in the drawings, a semi-spherical weight is shown it is to be understood that this weight may be made in any suitable type of artistic design, without departing from the spirit of this invention.

In Figs. 4 to 6 inclusive of the drawings, a modified form of the toy is shown, this 105 form being particularly adapted to be moved over the ground by a child, as in the manner of ordinary approved trundle toys. The modified form of toy comprises a body 30, which like the body 10 is constructed to 110 simulate the body of a human being, and this body or torso 10 is provided with a re-

cess 31 extending upwardly thereto from its lower end forming spaced arms 32 and 33 the inner surfaces of which are engaged by the upper portions of the sides of an axle 5 carrying frame 34. However, in the modified form of toy, the frame 34 is substantially in the shape of an inverted U, leaving the lower end thereof open, so as to permit the operating wheel 35 to project below 10 the lower end of the frame for engagement with a supporting surface as indicated at A in the drawings. The wheel 35 is carried by an axle 36 having the crank portion 37 and 38 upon its opposite ends, to which 15 crank portions legs 39 and 40 respectively of the toy are attached. The legs 39 and 40 are provided with slots 41 in their upper ends, opening out through the upper ends of the legs and extending at inclines therein, 20 which slots engage over or receive therein a pin 42, which extends through the torso or body 30. The pin 42 has a head 43 upon its outer end to prevent the legs 39 and 40 from moving longitudinally off the pin. 25 The wheel 35 has a relatively wide face, for engagement with the support A, and in use, the device is pushed over a support, such as the floor or the ground by means of a handle 45 which is threaded into the body or torso 30 10 from the back or otherwise suitably attached to the body 30 to permit a child to push the toy in front of him and when so pushed the engagement of the base of the wheel 35 with the ground or floor will rotate the crank axle 36, the crank portions of which will impart movement to the legs 39 and 40, moving them over the pin 42 and consequently simulating the movement of 35 a person walking.

40 Changes in details may be made without departing from the spirit of this invention, but;

45 I claim:

1. In a toy, the combination, of a body, 50 simulating a human torso provided with a recess extending upwardly thereinto from its lower end, a supporting frame extending into said recess, a crank axle rotatably carried by said supporting frame, and having crank portions on each end, a wheel mount-

ed on said crank axle for rotating the crank axle, legs for said body connected to the front portions of said axle, said legs provided with inclined slots in their upper portions opening out to their upper ends, a pin 55 extending transversely through said body and engaging through said slot to connect the legs to the body for permitting limited oscillatory movement of the legs upon rotation of the axle.

2. In a toy, the combination of a body simulating a human torso and provided with a recess extending upwardly from its lower end, a frame extending into said recess, a crank axle rotatably supported by said 65 frame, a crank portion formed upon the ends of said axle, a pin extending transversely through said body, legs for the body connected to the crank portion of said axle and provided with slots in their upper portions opening out through their upper ends, 70 said transverse means engaging through said slots, heads upon the ends of said pins to prevent said legs from movement laterally on the pin, and a weight depending 75 from the lower end of said frame.

3. In a toy, the combination of a body simulating a human torso and provided with a recess extending upwardly from its lower end, a rectangular frame having an 80 end and a portion of the sides thereof extending upwardly in said recess, means for fastening said sides to said toy, an axle rotatably supported by a portion of said frame, a crank portion formed upon the ends of 85 said axle, which extends exteriorly from the sides of said frame, a pin extending transversely through said body, rigid legs connected to the crank portion of said axle and provided with slots in their upper portions 90 opening out on their upper ends, said transverse pin engaging through said slots, heads upon said pin to prevent said legs from moving laterally on the pin, a wheel mounted upon said axle adapted to be rotated to rotate said axle and crank whereby oscillatory movement will be given 95 to the legs.

HARRY E. GREEN.
